CLAIM

The ornamental design for a display screen with graphical user interface, as shown and described.

DESCRIPTION

FIG. 1 is a front view of a first image of a display screen with graphical user interface showing my new design;

FIG. 2 is a second image thereof;

FIG. 3 is a third image thereof; and,

FIG. 4 is a fourth image thereof.

The appearance of the transitional image sequentially transitions between the images shown in FIGS. 1-4.

The dot-dot-dash broken lines illustrate a display screen or portion thereof and form no part of the claimed design. The dot-dash broken lines illustrate portions of the graphical user interface that form no part of the claimed design.

The subject matter in this design includes a process or period in which an image changes into another image. This process or period forms no part of the claimed design.
